PROCESS FOR PREVENTING THE DETRIMENTAL FORMATION OF LIME AND MAGNESIA SOAPS

Heinrich Bertsch, Chemnitz, Germany, assignor, by mesne assignments, to American Hyalsol Corporation, Wilmington, Del., a corporation of Delaware

No Drawing. Application December 5, 1930, Serial No. 500,438. In Germany December 13, 1929

10 Claims. (Cl. 87—5)

The disadvantages, which result from the formation of lime and magnesia soaps, particularly in the treatment of textiles, are known.

It has already been proposed to overcome these difficulties by adding sulphonated oily products, such as Monopol soap to the treatment baths in question, the composition of said soap being described in the German Patent No. 113,433.

According to this invention it has been found that the formation of lime and magnesia soaps in liquids, which, besides lime or magnesium salts, contain soap or Turkey red oils unresistant to lime, can be effectively prevented and any already precipitated fatty acid salts of calcium and magnesium be converted into a fine dispersion or brought into solution by adding the sulphonation products of higher aliphatic alcohols to the liquids. The requisite quantities are substantially less than those, which must be employed for obtaining the same effect with Monopol soap. The preferred procedure is to add the sulphonated alcohols or their alkali metal or ammonium salts referred to collectively hereinafter as "alkali salts" to the hard water before adding the soap or the Turkey red oil. In this case, if correct dosage is effected, absolutely no separation of lime or magnesium soaps takes place, and the solutions remain absolutely clear. If, on the other hand, the sulphonated alcohols are added only after the soap or the Turkey red oil, the strongly turbid liquor first becomes lighter in color and, after adding larger quantities of the sulphonated alcohol, the liquid becomes almost completely clear. The amount of sulphonated alcohols required to be added is, however, in this case greater than when the soap or the Turkey red oil is added to the already corrected water.

The sulphonated derivatives of the alcohols corresponding to the higher fatty acids, such as sulphonated octadecyl alcohol and sulphonated lauryl alcohol, have proved to be particularly suitable. In place of the last mentioned compound there can with advantage be employed the mixture of sulphonated fatty alcohols, which is obtained by converting the cocoanut oil acids into the corresponding alcohol mixture and sulphonating this mixture.

It has been found that the action of the sulphonated fatty alcohols is assisted if they are employed in admixture with secondary alkali phosphates. The secondary alkali phosphates include the alkali metal salts of pyro- and ortho-phosphoric acids. (Cf. Ephraim, "Anorganische Chemie", 1929, p. 621, lines 8 to 16; "General and Industrial Chemistry" by Molinari, Inorganic,

Second Edition, p. 416, lines 23 and 24; "A Course in General Chemistry" by McPherson and Henderson, Second Edition, p. 468, line 22.). A suitable mixture is, for example, 30 parts of secondary sodium phosphate per 70 parts of the sodium salt of the sulphonated lauryl alcohol.

In many cases it has proved to be advantageous also to add the said compounds to the water which is employed in the subsequent rinsing operation.

It should be understood that the terms "sulphonation" and "sulfonated" have been used throughout the specification and claims in their broad sense and hence the invention includes the use of sulfates as well as true sulfonates.

I claim:

1. In a process of rinsing fibrous materials treated with solutions of fatty acid derivatives unstable towards lime and magnesia salts, the method of preventing the detrimental effects of lime and magnesia soaps remaining as a result of such treatment characterized in that sulphonation products of the primary higher aliphatic alcohols are added to the rinsing liquids.

2. The process of eliminating the detrimental effects of lime and magnesia soaps in liquid treatment baths containing fatty acid derivatives unstable towards lime and magnesia salts comprising adding to the treatment liquid a sulfonated higher aliphatic alcohol.

3. The process as described in claim 2 wherein the sulfonated higher aliphatic alcohol is added to the treatment liquid prior to the addition of the fatty acid derivatives.

4. The process as described in claim 2 wherein the sulfonated higher aliphatic alcohol is added to the treatment liquid subsequent to the addition of the fatty acid derivatives.

5. The process of eliminating the detrimental effects of lime and magnesia soaps in liquid treatment baths containing fatty acid derivatives unstable towards lime and magnesia salts comprising adding to the treatment liquid a water soluble salt of a sulfonated higher aliphatic alcohol.

6. The process as described in claim 2 wherein the sulfonated alcohol is a monovalent normal primary higher aliphatic alcohol.

7. The process of eliminating the detrimental effects of lime and magnesia soaps in liquid treatment baths containing fatty acid derivatives unstable towards lime and magnesia salts comprising adding to the treatment liquid a water soluble salt of a sulfonated monovalent normal primary higher aliphatic alcohol.

8. The process of eliminating the detrimental

effects of lime and magnesia soaps in liquid treatment baths containing fatty acid derivatives unstable towards lime and magnesia salts comprising adding to the treatment liquid a sulfonated higher aliphatic alcohol and a secondary alkali metal phosphate.

9. The process of eliminating the detrimental effects of lime and magnesia soaps in treatment baths containing hard water and fatty acid derivatives unstable toward lime and magnesia salts

comprising adding to the water a sulfonated mixture of alcohols converted from a mixture of the acids of cocoanut oil.

10. The process of eliminating the detrimental effects of lime and magnesia soaps in liquid treatment baths containing fatty acid derivatives unstable towards lime and magnesia salts comprising adding to the treatment liquid the sulfonated alcohol, primary lauryl sulfate.

HEINRICH BERTSCH. 10
